AIR CIRCULATOR FOR HEATING UNITS
AND THE LIKEEugene G. Siegler and Raymond J. Siegler,
Marion County, Ill.

Application December 15, 1938, Serial No. 245,880

3 Claims. (Cl. 126—110)

This invention relates to air circulators for heating units and the like such as units or devices used for conditioning air for housing habitation purposes, and comprises the application of improved air entraining means to the unit, as a primary purpose of the invention.

Another object is to provide a unit for conditioning air with improved means for providing a maximum of conditioned air circulation from the unit, into a room or abode where the unit may be located.

A further object is to provide the unit with means to entrain the air into the unit and to discharge the air from the unit in the approximate plane of entrainment thereto.

A still further object is to provide means to entrain the air upwardly through the unit from a low plane, and also to discharge the conditioned air from the unit in a relatively low plane.

Still another object is to provide a unit for conditioning air with an air entraining passageway having its intake end disposed relatively low with respect to the unit and to dispose the passageway over the unit and down to a place of discharge which is also disposed relatively low with respect to the unit.

Other objects and advantages will appear as this description progresses and by reference to the drawings, in which:

Figure 1 is a vertical longitudinal sectional elevation of a heating unit showing the application of the invention thereto and the elevation being taken approximately on the line 1—1 of Fig. 2.

Figure 2 is a vertical transverse sectional elevation taken approximately on the line 2—2 of Fig. 4.

Figure 3 is a horizontal sectional elevation taken approximately on the line 3—3 of Fig. 1.

Figure 4 is a horizontal sectional elevation taken approximately on the line 4—4 of Fig. 1.

Referring by numerals to the accompanying drawings, 5 designates a casing which in this instance of disclosure is of rectangular shape in cross section, as shown in Figs. 3 and 4, and the casing at its lower end being provided with corner supports 6 for mounting on the floor or foundation and the casing in its side walls and front wall between said supports having arched cut away portions 7 to allow air entrainment into the casing from the bottom thereof. The casing 5 is provided with a top wall 8 having an opening 9 and mounted on the top wall 8 is a cover 10 supporting a grill plate 11.

Disposed within the casing 5 and annularly spaced from the vertical walls thereof is a vertically extending combustion chamber 12, said combustion chamber resting on and being secured to a bottom wall 13 which is secured to and between a pair of horizontally extending angle members 14 which are secured at their ends to the front and rear walls 15 and 15a respectively, of the casing 5.

Depending from the bottom wall 13 of the combustion chamber 12 is a fire pot 16 having a vent opening 17 in its lower end, and an intermediate disposed pilot ring 18 and a top ring 19, the fire pot 16 and elements 18 and 19 thereof forming parts of an oil burning device, and leading to the lower end of the fire pot 16 is a fuel vapor supply pipe 20 which leads from a float chamber 21 which receives its liquid fluid through the pipe 22 which leads from a supply tank 23.

20 The supply tank 23 is supported in the upper compartment 24 of a casing 25 which is disposed against the rear wall 15a of the casing 5, as shown in Figs. 1 and 3, and located in the lower compartment 26 of the casing 25 is a blower 21 having its outlet end 28 secured to the rear wall 15a of the casing 5 and in communication with the horizontal run 29 of a passageway 30 which communicates with the lower end of the vertical run 31 of said passageway, the upper end of the vertical run 31 communicating with a manifold 32 which is extended horizontally across the top 33 of the combustion chamber 12.

As shown, the passageway 30 and the manifold 32 with which it communicates are disposed within the casing 5, the vertical run 31 of the passageway being disposed adjacent one side of the combustion chamber 12, and the bottom wall of the manifold 32 is provided by the top 33 of the combustion chamber 12.

40 Depending from the top 33 of the combustion chamber 12 are a series of necks 34 which are in an alining row sidewise of the top 33, and adjacent the rear wall 35 of the combustion chamber 12 and depending from each neck is the upper end of a tube 36, each tube at its lower end being engaged over a respective upwardly extending neck 37, the necks 37 being in an alining row like the necks 34 on the top 33, said necks 37 being formed on the top wall 38 of a manifold 39 which is supported from the rear wall 35 of the combustion chamber 12.

Obviously, the tubes 36 and the manifold 39 with which they connect are disposed within the 50 combustion chamber 12, and depending from the

bottom of the manifold 39 adjacent each end is a tubular extension 40 each being connected within a joint 41 of a respective discharge tube 42, each discharge tube 42 having a band 43 for providing a horizontally extending discharge end 44, the discharge ends of said tubes 42 converging towards each other and being connected with an outlet box 45 which is secured to the front wall 15 of the casing 5 and in communication with the grille plate 46 which is also mounted on said front wall of the casing on the outside thereof.

Leading from the upper end of the combustion chamber 12 in the rear wall 35 of said chamber is a sleeve 47 to which the stack 48 is mounted for discharge of the products of combustion from the chamber 12, and provided in the rear wall 49 of the casing 25 at the bottom thereof, is a pair of spaced openings 50 through which air is entrained and filtered by passing through respective filtering pads 51 which are removably mounted in the lower compartment 26 in horizontal guides 52 across respective openings 50, as shown in Figs. 1 and 3, when air is entrained through the openings 50 by operation of the blower 27.

From an inspection of Fig. 1, it is to be noted that the inlet openings 50 and their respective filtering pads which are located at the rear of the unit and the outlet box 45 at the front of the unit with which the discharge ends of respective discharge tubes 42 communicate while being disposed at a low level with respect to the unit, are also approximately on the same horizontal plane, and with this arrangement of specific location of inlet and outlet for air entrainment through the unit and discharge therefrom, a maximum of conditioned air displacement is afforded by reason of the low point of entry to the unit and the low point of discharge from the unit owing to the cooler air currents being taken from the bottom of a room and discharged after conditioning has been effected, at the bottom of the room or floor level approximately.

The unit is put in operation by igniting the oil or gas vapors in the fire pot 16 for subsequently combusting the gases in the chamber 12, and the motor 53 which is connected to the shaft 54 of the blower 27 upon being started will revolve the rotor 55 a required speed. Air currents at the approximate floor level of the room in which the unit is located will be drawn through the filtering pads 51 and into the blower and will be discharged therefrom through the outlet end 28 of the blower into the horizontal run 29 of the passageway 30 and through the vertical run 31 to the horizontal manifold 32 and downwardly through the tubes 36 and into the lower manifold 39, the air currents traversing the upper manifold 32, and the tubes 36 to the lower manifold 39 receiving a maximum of heat by reason of the manifolds 32 and 39 and connecting tubes 36 being disposed in the combustion chamber 12.

With the disposition of the manifolds 32 and 39 and their connecting tubes 36 within the combustion chamber 12, it is quite obvious that a maximum discharge of heated air from the outlet box 45 will be a result, and by taking the cooler air from the lower plane of a room into the conditioning unit and discharging the conditioned air into the room on a low plane, a maximum of air movement in the room is effected, by reason of the discharging conditioned air at the low level with respect to the floor of the room, rising to a greater height with a consequent larger air

disturbance being brought about by the higher travel of the conditioned air. Further, the air intake from a low plane in a room will convey a maximum volume of dust laden air to the filtering pads where it will be retained with a resultant cleaner air discharge.

By reason of the combustion chamber 12 being free of opposing side walls of the casing 5, the cut away portion 7 of the casing will allow air entrainment into the lower end of the casing, and upon becoming heated will rise and pass through the opening 8 of the top wall 8 of the casing and will be discharged through the grill plate 11 which is mounted on the cover 10 of the unit.

While we have described one embodiment of our invention with some particularity, obviously many other embodiments thereof may occur to those skilled in the art to which it appertains. We, therefore, do not limit ourselves to the precise details described, but claim as our invention all variations and modifications coming within the scope of the subjoined claims.

What we claim is:

1. A unit for conditioning and circulating air comprising a combustion chamber, a fire pot beneath said chamber, a manifold disposed adjacent the top of said chamber, a vertically walled air entraining passageway in communication with said manifold and disposed on one side of the chamber and having its intake end disposed adjacent the lower end of the unit, a second manifold disposed within said chamber adjacent the lower end thereof, depending tubes connecting said manifolds, and a discharge pipe leading from each end of the lower manifold and having their outlet ends extending beneath the fire pot adjacent the lower end of the unit.

2. A unit for conditioning and circulating air comprising a casing having a combustion chamber therein, a manifold disposed adjacent the top of said chamber, a vertically walled air entraining passageway in communication with said manifold and having its intake end disposed adjacent the lower end of the unit and disposed on one side of said chamber, a second manifold disposed within said chamber adjacent the lower end thereof, depending tubes connecting said manifolds, and a pair of spaced discharge pipes leading from the lower manifold and having their outlet ends disposed adjacent the lower end of a wall of the casing beneath the chamber and in opposite relation to the intake end of the passageway.

3. A unit for conditioning and circulating air comprising a casing having a combustion chamber therein and a fire pot depending from the combustion chamber, a manifold forming the top of said combustion chamber, a lower disposed manifold in said combustion chamber, tubes disposed between said manifolds and connected at their ends therewith, a discharge pipe leading from respective ends of the lower manifold and having their extending ends inclined beneath said fire pot, a walled air entraining passageway leading from the lower end of said casing to said first mentioned manifold and being disposed on one side of the combustion chamber, and an outlet box positioned in the lower end of a wall of said casing with which the extending ends of said discharge pipes communicate.

EUGENE G. SIEGLER.
